Primary Examiner — Jack Reickel*Assistant Examiner* — Keith J Wilson(74) Attorney, Agent, or Firm — Tucker Ellis LLP(57) CLAIM

The ornamental design for a tray, as shown and described.

DESCRIPTION

FIG. 1 is a perspective view of a tray showing our new design.

FIG. 2 is a front view thereof.

FIG. 3 is a rear view thereof.

FIG. 4 is a right side view thereof, a left side view being a mirror image.

FIG. 5 is a top view thereof; and,

FIG. 6 is a bottom view thereof.

The broken lines shown represent portions of a tray and form no part of the claimed design.

1 Claim, 6 Drawing Sheets(56)
